UNITED STATES PATENT OFFICE.

WILHELM MAYER, OF STUTTGART, GERMANY.

DESIGN FOR A MEMORIAL SHIELD.

SPECIFICATION forming part of Design No. 21,862, dated September 20, 1892.

Application filed May 31, 1892. Serial No. 435,127. Term of patent 3½ years.

To all whom it may concern:

Be it known that I, WILHELM MAYER, manufacturer, a subject of the King of Würtemberg, residing at Stuttgart, in the Kingdom of Würtemberg, Germany, have invented and produced a new and original Design for a Memorial Shield, of which the following is a specification, reference being had to the accompanying drawing, forming part thereof.

10 The leading feature of my design consists of a circular shield bearing on its face a number of medallions illustrating the discovery and progress of America and showing the portraits of some American celebrities, the whole 15 designed as a commemoration of the discovery of America. In the center of the shield is a medallion showing a winged female figure uncovering a sphere on which is seen a geographical outline of America. Surrounding this are 20 two concentric rings of shields displaying the arms of the various States of the United States of America, each shield bearing the arms of a different State. Two ornamental scrolls are placed, one at each side of the center medallion, 25 upon the two concentric rings of shields. At equal distances around the outer ring of shields are eight medallions bearing, respectively, representations of "Landing of Colum-

bus," "Landing of the Pilgrims," "Battle of Lake Erie," "Washington Crossing the Delaware," "Declaration of Independence," "Battle of Churubusco," "Emancipation Proclamation," and an allegorical design of industrial progress. These eight medallions are placed a small distance apart from each other, and in 30 the outer portion of each of the spaces thus formed is placed one of eight smaller medallions, on which are represented heads of George Washington, Benjamin Franklin, Abraham Lincoln, James A. Garfield, Ulysses 35 Grant, Thomas Jefferson, H. Wadsworth Longfellow, and Sam. F. B. Morse. In the inner portion of each of these spaces is an ornamental shield, and at the head of the shield is an American eagle with scroll. 40 45

What I claim is—

The design for a memorial shield, as herein shown and described.

In testimony whereof I have signed my name to this specification in the presence of 50 two subscribing witnesses.

WILHELM MAYER.
